BROODER ATTACHMENT FOR WOOD
HEATERS

Camb J. Ashley, Goodloe, Va., assignor to Automatic Draft and Stove Company, Guinea, Va.

Application December 23, 1932, Serial No. 648,696

5 Claims. (Cl. 236—6)

My invention relates to improvements in brooder attachments for wood heaters.

One object of my invention is to provide a brooder attachment for an ordinary down draft wood heater having means to automatically regulate the draft of the heater whereby the desired temperature can at all times be maintained in the brooder.

Another object of my invention is to provide 10 an attachment of this character which can be readily applied to the ordinary down draft heater without altering the construction of the heater in any way and which has the same operation and advantage as a brooder having a specially 15 constructed heater.

A further object of my invention is to provide 20 an attachment of this character in which the automatic control of the damper is so positioned it will not be affected by the direct heat from the heater and in which the automatic control can be 25 regulated to the desired temperature.

A still further object of my invention is to provide 30 a simple, cheap and effective brooder attachment for wood heaters having certain details 25 of structure and combination of parts herein- after more fully described.

In the accompanying drawings:—

Figure 1 is a side elevation of an ordinary down 35 draft wood heater with my attachment applied, forming a complete automatically controlled brooder.

Figure 2 is a top plan view of Figure 1.

Figure 3 is a vertical transverse sectional view 40 taken on the line 3—3 of Figure 1.

Figure 4 is a vertical sectional view taken on the line 4—4 of Figure 3 at right angles to Figure 3 and looking in the direction of the arrow.

Figure 5 is a vertical sectional view of a modified form of the down draft pipe.

Figure 6 is an enlarged perspective view of the base attaching means.

Referring now to the drawings:—

1 represents the ordinary down draft wood heater having the down draft pipe 2 extending 45 upwardly close to the body of the heater to a point adjacent its upper end. These heaters are mounted on legs and the upper end of the body is provided with a cover 3 by means of which the wood is fed to the stove. The heater is also 50 provided with the usual stove pipe 3' extending from the upper end, but this stove pipe could extend from the side of the heater. The upper end of the down draft 2 is provided with the ordinary hand operated shutter damper, as is well understood by those skilled in the art. My im-

proved brooder attachment comprises a circular band 4 of flexible sheet metal provided with a series of openings 5 to allow the air to circulate under the body of the heater. This band is provided on its inner face with inwardly extending lugs 6 adapted to be sprung into the socket from which the ordinary legs of the heater have been removed. By this structure it will be seen that the small chickens cannot get under the stove or crowd each other due to the fact that the same 10 is of a circular form. The hood 8, forming the top of the brooder, is composed of a conical circular ring having the opening 9 therein of a size to closely fit the outer wall of the body 1 of the heater and is supported by means of legs 10 15 so that its lower edge is supported a distance from the floor so that the chickens can readily pass under the same.

In order that this hood may be readily slipped down over the heater, it is provided at one side 20 with a cut away portion 11 of a size slightly greater than the down draft pipe 2 and the thermostatic control damper carrying housing 12, as clearly shown in Figures 2 and 4. By this structure it will be seen that the hood 8 can be slipped 25 down around the stove until the legs 10 rest upon the floor. In order to make a tight fit around the down draft pipe 2 and completely close the opening 11, after the hood has passed the automatic damper control housing 12, I provide two 30 sheet metal plates 14 and 15 pivoted at 16 to the hood 8 and having their inner edges 17 and 18 arranged in an arc or circle to correspond with the body of the heater 1. In beyond these curved edges, the plates are provided with cut away 35 portions 19 and 20 adapted to correspond with the curve of the down draft pipe 2 and whereby the plates 14 and 15 are moved inwardly and a tight fit is made with the body of the stove and the down draft pipe to retain the heat under the 40 hood. In order to hold the plates in the operative position, I provided buttons 21 and 22 which are adapted to be turned over the edges of the plates 14 and 15 to hold them in their operative 45 position.

The ordinary wood heater of this type, as heretofore stated, is provided with a hand operated damper at the upper end of the down draft pipe. This damper is in the form of a cap effect extending around the upper end of the down draft 50 pipe and bolted thereto, which bolt extends over and secures the draft pipe to the body of the stove.

In converting this ordinary wood heater to a brooder, this cap is removed and a cap 23 is placed 55

at the upper end of the down draft pipe 2. This cap 23 has an annular flange 24, a short distance in beyond the outer edge thereof and which extends downwardly into the upper end of the down draft pipe 2. The opposite sides of this flange are provided with downwardly extending ears 25 and 26, provided with openings through which small bolts 29 and 30 extend and which also extend through the openings in the upper end of the down draft and whereby the cap is firmly locked upon the upper end of the down draft pipe. The flange 24 is also provided with the ear 31 to which is bolted by the bolt 32, the casting 33, forming a housing which carries the thermostatic control for the damper. This casting has on its upper face the upwardly extending ears 34 and 35 in which are mounted the trunnions of the damper operating lever 36. This lever has the outwardly extending arm 37 extending over the cap 23 and has loosely mounted thereon, a link 38 which extends downwardly through the web 39, extending across the opening 40 in the upper end of the cap 23. The lower end of this link has loosely mounted thereon, a disc damper 41 which is adapted to close the opening 40 which the lever 36 is moved upwardly as shown in Figure 3. The casting 33 has secured to its rear face, a shield plate 42 which extends downwardly and is turned outwardly as indicated at 43. Secured to the shield plate 42 is a narrow strip 43' which extends parallel with portion 43. Supported by this strip 43' is the ordinary commercial ether wafer 44 which is provided on its lower face with projection 45 passing through an opening 45' in the strip 43'. A rod 46 engages the upper face of the ether wafer and is free to move vertically through the bearing 47 carried by the casting 33 and extends upwardly above the upper face of the casting 33 directly below the damper operating lever 36. The damper operating lever 36 is provided with a set screw 48 passing therethrough and adapted to engage the upper end of the rod whereby the proper adjustment for the lever is obtained.

The cap 23 is provided with the hand operated damper 49 pivoted at 50 and having an arc shaped slot 51 therein to allow the same to be freely moved over the opening in the cap around the link connecting the damper with the operating lever. In Figure 5, the down draft pipe 2 is provided with the outwardly bulged portion 52 which allows a greater amount of air to pass around the damper when it has reached its lowermost position. The rear end of the damper operating lever 36 is provided with an opening 53 into which a rod 54 may be secured for carrying a sleeve 55 to which a cable may be attached for operating a ventilator which may be remote from the heater. The lever 36 at its outer end has the sleeve 56 slidably mounted thereon and slidably held thereon by a set screw 57 whereby it can be adjusted. The upper end of the sleeve 56 is provided with an eye 58 to which a cable can be attached for opening a ventilator which may be in some distant part of the room.

By the structure herein described, it will be seen that I have provided an attachment for the ordinary down draft air tight heater whereby it is converted into a brooder and in which the hood can be readily removed and the stove used for the ordinary heating purposes.

Having thus fully described my invention, what I claim is:—

1. The combination with an air tight wood heater having a down draft pipe extending along the side thereof, a flanged cap engaging within the upper end of the down draft pipe and having an opening therein, a casting carried by one side of said cap, a lever pivoted on the upper face of the casting, a thermostatic damper control carried by the casting and operating the lever extending over the opening in the cap, a damper loosely carried by the lever within the down draft pipe and a sleeve adjustably carried by the lever and having an eye to which a ventilator operating cord is adapted to be attached.
2. The combination with an air tight wood heater having a down draft pipe extending along the side thereof, a flanged cap engaging within the upper end of the down draft pipe and having an opening therein, a casting secured to one side of the cap, a shield plate carried by the inner end of the casting, a thermostatically operated damper control carried by the casting, a lever pivoted on the upper face of the casting and operated by the damper control and extending over the opening in the cap, a link loosely mounted upon the lever and extending into the down draft pipe, a damper carried by the link and closing the opening in the cap.
3. The combination with an air tight wood heater having a down draft pipe, a flanged cap engaging within the upper end of the down draft pipe, a damper carried by the cap, a housing carried by the cap, a narrow strip extending across said housing, an ether wafer supported by the strip, and means operated by said wafer for operating the damper.
4. A means for converting a down draft heater into a brooder heater comprising a cap provided with a flange adapted to telescope the upper end of the down draft pipe and having an opening therein, a casting carried by one side of the cap, a lever pivoted on the upper face of the casting, a thermostatic damper control carried by the casting and operating the lever extending over the opening in the cap, a damper loosely carried by the lever, and a sleeve carried by the lever and having means to which a ventilator operating cord is adapted to be attached.
5. A means for converting a down draft heater into a brooder heater comprising a flanged cap adapted to engage within the upper end of the down draft pipe, a damper carried by the cap, a housing carried by the cap, a narrow strip extending across said housing, an ether wafer supported by the strip, and means operated by said wafer for operating the damper.

CAMB J. ASHLEY.
